UNITED STATES PATENT OFFICE.

STEPHEN G. WILSON, OF PHILADELPHIA, PENNSYLVANIA.

BROOM-TENSIONING DEVICE.

Application filed March 16, 1922. Serial No. 544,139.

To all whom it may concern:

Be it known that I, STEPHEN G. WILSON, a citizen of the United States, residing in the city and county of Philadelphia, State 5 of Pennsylvania, have invented a new and useful Broom-Tensioning Device, of which the following is a specification.

My present invention comprehends a novel broom tensioning device. When one 10 side of the broom is used for heavy sweeping, such as for example porches and pavements, the broom straws are less resilient and harder than they are when the opposite side of the broom is used for indoor or light 15 sweeping, such as carpets and rugs. The tensioning device can also be adjusted to cause the broom straws on both sides of the broom to be either less resilient or more resilient.

20 Other novel features of construction will hereinafter more clearly appear in the detailed description and the appended claims.

The invention is satisfactorily illustrated in the accompanying drawing, but the important instrumentalities thereof may be varied, and so it is to be understood that the invention is not limited to the specific details shown and described, as long as they are within the spirit or scope of the claims.

30 Figure 1 represents a side elevation of a broom embodying my invention.

Figure 2 represents a vertical section of a portion thereof on line 2—2 Figure 3.

35 Figure 3 represents a transverse section on line 3—3 Figure 2, on an enlarged scale.

Figure 4 represents a perspective view of a cap employed.

Figure 5 represents a perspective view of the detachable side arms employed.

40 Figure 6 represents a longitudinal section of the arm shown in Figure 5.

Figure 7 represents a perspective view of a frame employed.

45 Figure 8 represents a perspective view of an encircling band of a plurality of straps for the broom, and straps therefor.

Figure 9 represents a perspective view of concaved guide roller bearings applicable to the side arms for guiding the tension straps therein.

50 Figure 10 represents a side elevation of a pressure spring applicable to the sides of the side arms.

Figure 11 represents a transverse vertical

section of a detached portion, on line 11—11 55 Figure 8.

Figure 12 represents a perspective view of a portion of one of the side arms employed.

Figure 13 represents a section of a screw or button for adjusting the frame in position on the sleeve of the handle of the broom.

Figure 14 represents a vertical section of a detached portion, showing the manner of locking the side arms to the cap.

Figure 15 represents a horizontal section on line 15—15 Figure 8.

Figure 16 represents a perspective view of the lower end portion of the side arms.

Similar numerals of reference indicate 70 corresponding parts in the figures.

Referring to the drawings,

1 designates the handle of a broom embodying my invention. A sleeve 2 is fixed to the lower end of the handle by means of a fastening device 2^{xx}, and such lower end has a chamber 3, the walls of which are divided in quarter or other sections 3^x, and are adjusted outwardly by the screw 4, see Figures 2 and 3. 6 is a screw engaging a core 5 at the upper end of the stub handle 5^x and said core has an annular bead 3^{xxx}, so that when the core 5 is assembled in the chamber 3, there will be a perfect fit, yet the frictional grip between the parts will be 85 reduced, and the parts will be easy of separation.

The core 5 is split to form the quarter or other sections 3^{xx} and has the central aperture 36 bevelled at its upper portion, as at 35, 90 so that by adjustment of the screw 6 the core 5 can be expanded or permitted to contract. The sleeve 2 has a cap 7 fixed to it. The construction of the cap 7 is best seen in Figures 2 and 4 and such cap has four sides 95 turned down from the top which latter has an opening 7^x to receive the sleeve 2. The opposite sides 8 have their lower ends turned inwardly and upwardly forming hook shaped flanges 9. The top has the slots 10 in proximity to the downwardly inclined side flanges 12 which act as springs against which the side arms 13 rest and which hold them in an extended position. The top has the lower ends of the sleeve 2 in the openings 7^x. The sleeve 2 is fixed to the stub handle 5^x by the screw 2^x. 13 designates side arms 100 of channel formation which taper down-

wardly and are narrower at their lower portions so as to receive and embrace the opposite edge portions of the head 42 of the broom. The side arms 13 terminate at their upper ends in channelled tongues 14, see Figures 5, 12 and 14. The juxtaposed walls of the side arms rest on the spring flanges 12 of the cap 7, see Figure 14, and the channelled tongues extend into the apertures 10 and bear against the bottom face of the top of the cap 7. The channelled ends of the tongues 14 rest against the inner face of the spring flanges 12 locking them to said cap 7, see Figure 14.

15 15 designates a resilient frame formed of spring material and having an apertured base to adapt it to be adjustably mounted on the sleeve 2. The frame 15 has four upwardly directed arms, see Figure 7, the upper ends of two of which are curved outwardly and downwardly, as at 16, and provided with slots 17. The other two arms are arranged opposite to each other and one of them has a button 15* and an inturned locking tongue 34, see Figure 7, which is adapted to enter a desired crosswise opening 33 in the sleeve 2, see Figure 1.

The side arms 13 embrace the opposite edges of the broom head and serve also as guides for straps 18 which are made preferably of spring metal and have the lugs 30 both of which pass between concave rollers 19, see Figures 6, 9 and 19, and over an inwardly deflected opened strip 19*, forming a shoulder 19** which limits the movement of a juxtaposed strap in one direction. The axles 20 see Figures 5 and 16, of the rollers 19 pass through slots 20* in the side arms 13 and are then bent laterally, see Figure 5, to secure them in position. The straps 18 pass through openings 13** in the shoulders 13*, see Figure 6, and also Figure 12. The lower ends of the side arms 13 are deflected laterally and inwardly and are scalloped, see Figure 16. The straps 18 have the lugs 30, see Figures 1 and 6, which when the straps 18 are raised and have the lug 30 interlocked with the scallops 30* will prevent oscillating movement of the straps 18 in the side arms 13 in which they are guided, making the straws stiff on both sides of the broom at the same time. The upper ends of the straps 18 are in the form of T-shaped heads 21, see Figure 5, which are sprung into the slots 17 of the frame 15, see Figures 1 and 7. The sides of the side arms 13 near their upper portion, see Figure 6, have the end 13*** which play within the hook shaped flanges 9 of the cap 7, see Figures 2 and 4, holding said parts close together.

The lower end of the straps 18 are enlarged and slotted as at 22**, see Figure 8, and one section on each strap 18 thus formed has its outer free end inturned to form flanges 22, see Figures 11 and 8.

The lower end of each enlarged section of a strap 18 is apertured and has in the upper and lower walls of such aperture the outwardly directed recesses 23. The function of these recesses 23 is to receive the locking ends 24 of the straps 25 four of which are employed. The locking end 24 is formed by bending the free end of a strap 25 inwardly and then outwardly and in assembling a strap it passes into the oppositely disposed recesses 23 in rear of the tongues formed by recesses and its free end then extends outwardly through other recesses 23, as will be understood by Figures 8 and 11. I have shown a plurality of recesses so that opposite straps can be relatively adjusted in accordance with the thickness of the broom which is employed. The straps 25 form an encircling band 26. A strap 25 on one side of the broom is provided in proximity to its free end with the serrations 27 with which are adapted to engage one of the clips 28 carried by a juxtaposed strap 25. The two overlapping straps 25 on one side of the broom are provided with the grasping portions or finger portions 29 whereby the longitudinal adjustment of such straps can be adjusted. The two straps 25 on the opposite side of the broom overlap each other and each strap 25 is provided with a clip 28 which overlaps the juxtaposed strips and holds them together, see Figure 8.

The side arms 13 are resiliently held against the spring flanges 12 of the cap 7 by means of the springs 32, see more particularly Figures 1 and 10.

The operation will now be clear to those skilled in this art and is as follows:—

When it is desired to assemble a broom head with respect to the handle, the stub 5 is inserted into the position seen in Figure 2 and the screws 2* screwed into place. Before this is done, the straps 25 at the rear of Figure 8 are opened and when such straps are raised to disconnect the clips 28, the locking together of the overlapping straps 25 seen at the front portion of Figure 8 is not effected because of the divided end of the strap 18 to which they are connected.

Assuming now that the parts are in the position seen in Figure 1, the parts are so adjusted that the straps 18 are free to move in one direction and their movement in the opposite direction will be limited by the shoulders 19**, see Figure 5. If the broom is now moved so that the face of the broom seen in Figure 1 is moving nearest to the floor in a sweeping direction, the straps 18 will abut against the shoulders 19* so that when such side of the broom is used the straws will be stiff, that is, the broom corn below the encircling band 26 will all be stiff and relatively hard and less resilient. If now the broom is used to sweep in the opposite direction, in other words, the oppo-

site side of the broom is being used, the straps 18 will be free to move until they abut against the side of the side arms 13 so that the broom straws will have more play 5 above and below the encircling band 26 and will be more resilient and will not be so stiff as they were before. They can thus be used for soft and light sweeping.

In the operation thus described, the locking member 34, see Figure 7, is in the lowermost slot or opening 33, see Figure 1. If it is desired to have the broom straws hard and less flexible when the broom is used for sweeping in either direction or, in other 15 words, when either side of the broom is to be used as in sweeping back and forth, the frame 15 is raised until the locking member 34 engages the slot 33 marked "Hard", see Figure 1. When the straps 18 are raised in 20 this manner, their lugs or ribs 30 will engage the scallops 30*, see Figure 16, on the side arms 13, so that relative lateral or oscillating movement of the straps 18 in the side arms 13 is prevented and the broom 25 straws will now be hard and less resilient on both sides of the broom at the same time irrespective of the direction in which the 30 sweeping action takes place or the side of the broom which is being used. If the encircling band 26 is now adjusted to a higher position or, in other words, in proximity to the lower ends of the side arms seen in 35 Figure 1, the broom straws below the encircling band will be flexible and resilient on both sides of the broom at the same time or, in other words, softer, irrespective of which side of the broom is used in sweeping.

It will be apparent from the foregoing 40 that the tensioning device can be adjusted so that when one side of the broom is used the broom straws will be hard and when the opposite side of the broom is used, the broom straws will be soft and flexible.

When the tensioning device is locked by the engagement of the locking lugs or ribs 30 with the scallops 30*, both sides of the broom will be hard and relatively stiff irrespective of the direction in which the 50 sweeping action takes place.

The tensioning device can also be adjusted so that both sides of the broom will be soft and flexible irrespective of the direction in which the sweeping action takes place, that 55 is, when both sides of the broom are being used.

The encircling band 26 can be longitudinally adjusted and if it is desired to tighten the band around the broom, the grasping handles 29 are moved toward each other thereby drawing together the overlapping straps 25 to which they are connected. This causes the enlarged head sections to which they are connected to press 60 inwardly on the inwardly and laterally de-

flected tongues 22* which will at the same time adjust the opposite straps 25, see more particularly Figure 11, so that the effective length of the encircling band 26 is reduced. By a reverse adjustment the effective length 70 of the encircling band can be increased. If it is desired to decrease the width between opposite straps 25, see Figure 8, the locking ends 24 at each outer end of the straps 25 are removed from the outer recesses 23 with 75 which they engage and are moved into engagement with the inner recesses 23, so that the straps 25 on either side of the broom will then be closer together and will more firmly grip the broom straws, it being understood 80 that the two straps at each end may be adjusted in the same manner. The rear straps 25 seen in Figure 8 can be opened without affecting the locking engagement of a clip 28 with the serrations 27, since when 85 such straps are raised to open them the inwardly projecting tongues 22* will move freely inwardly without engaging the opposite enlarged head section, while when the two straps 25 on the front side seen in Figure 9 are drawn together, the head sections to which they are connected will engage and press inwardly the deflected tongues 22* and therefore draw inwardly 90 the head section to which it is connected 95 which will draw the straps 25 on the opposite side of the band 26 together also.

It will be understood from Figure 14 that the side arms 13 are locked with respect to the cap 7, see Figure 4, since as seen in Figure 14, the side flanges of the locking tongues 14 will engage the inner wall of the spring flanges 12 and thus prevent the disengagement of the side arms 13 from the cap 7. The rollers 19, see Figure 9, between 100 which the strap 18 passes are made concave so as to reduce the wear on the plating of such strap 18 and also so as to permit the lugs 30 to freely pass between them.

Having thus described my invention, what 110 I claim as new and desire to secure by Letters Patent, is:

1. In a broom tensioning device, a longitudinally adjustable band encircling the sweeping part of the broom, straps at the 115 edges of the broom and connected with said band, supporting means for said straps and means co-operating with said straps to permit their movement in one direction and to restrict their movement in an opposite direction.

2. In a broom tensioning device, a longitudinally adjustable band encircling the sweeping part of the broom, straps at the 125 edges of the broom and connected with said band, supporting means for said straps, means co-operating with said straps to permit their movement in one direction and to restrict their movement in an opposite direction, and means to lock said straps to 130

prevent their movement in either direction with respect to their supporting means.

3. In a broom tensioning device, a band encircling the sweeping part of the broom, straps connected with said band and extending upwardly along the edges of the broom, side arms embracing the head of the broom and in which said straps are guided, said side arms having means to limit the movement of said straps in one direction, said side arms and straps having adjustable interlocking means to prevent relative lateral movement of said straps in said side arms, and a frame connected with said straps and provided with means to lock it in the position to which it has been adjusted.

4. In a broom tensioning device, an encircling band engaging the broom straws, a cap fixed to the broom and having spring side flanges, side arms embracing opposite edges of the head of the broom detachably connected with said cap and adapted to rest on said side flanges, resilient means to draw said side arms toward each other and against said side flanges, straps connected with said band and guided in said side arms, and a frame to which said straps are connected and provided with means to lock it with said handle.

5. In a broom tensioning device, the combination with a broom, of a cap fixed to the broom handle and having oppositely disposed spring flanges and apertured in proximity to said flanges, side arms having locking tongues entering said apertures and engaging the inner walls of said spring flanges, said side arms being adapted to embrace opposite edge portions of the broom head, a frame slideable on said handle and having a locking member engaging said handle to secure the frame in adjusted positions, straps guided in said side arms and connected with said frame, said side arms having an inwardly deflected portion to limit lateral movement of said straps in one direction, said side arms having scallops, lugs on said straps to engage said scallops and prevent relative lateral movement of said straps and side arms when the straps are raised, and a longitudinally and laterally adjustable band to surround the broom straws and connected with said strap.

6. In a broom tensioning device, the combination with a broom, of a sleeve fixed to the handle, a cap secured to said sleeve, side arms to embrace opposite edges of the broom head and detachably connected with said cap, resilient means connected with said side arms to draw them toward each other, a frame adjustable on said sleeve and having means to interlock therewith, straps connected with said frame and guided by said side arms, said side arms having means to limit lateral movement of said straps in one

direction, and a band connected with the lower ends of said straps and adapted to encircle the broom straws.

7. In a broom tensioning device, an encircling band adapted to surround the broom straws and comprising a plurality of straps having their ends overlapping, each strap having a clip to engage the juxtaposed strap, the strap at one side having serrations with which the clip of its juxtaposed strap is adapted to engage, straps having a slot at their lower ends contributing to form enlarged head sections, each of which is apertured, the opposite upper and lower walls of such apertures having recesses, the straps in proximity to said head sections having deflected locking portions to seat in said recesses, one head section of each strap having a tongue to overlap the juxtaposed head section, and supporting means carried by the broom and to which said straps are connected.

8. In a broom tensioning device, the combination with a broom, of a sleeve connected with the handle, a cap secured to said sleeve and having spring flanges, side arms movably connected with said cap and adapted to embrace opposite portions of the broom head, resilient means to hold said side arms against the spring flanges of said cap, said side arms having inwardly deflected open strips having shoulders at one end thereof, a frame adjustable on said sleeve and having means to interlock therewith, straps connected with said frame guided by said side arms having their lateral movement in one direction limited by said shoulders of said strip and being free to move in the opposite direction, and a band encircling said broom straws and connected with said strap.

9. A broom tensioning device, comprising a sleeve adapted to be connected with the broom handle, a cap fixed to said sleeve, side arms movably connected with said cap and adapted to embrace opposite portions of the broom head, resilient means to draw said side arms towards each other, concave rollers carried by said side arms, straps guided by said rollers and free to move laterally in one direction, said side arms having means to limit the movement of said straps in an opposite direction, a frame adjustable on said sleeve having means to interlock therewith to secure it in its adjusted position and connected with said straps, and a longitudinally and laterally adjustable band connected with said straps and adapted to surround the broom straws.
